J. H. MILLER.

GREASE CUP.

APPLICATION FILED JAN. 29, 1921.

1,393,304.

Patented Oct. 11, 1921.

Inventor

J. H. Miller

By Watson E. Coleman
Attorney

UNITED STATES PATENT OFFICE.

JACOB H. MILLER, OF CRESSON, PENNSYLVANIA.

GREASE-CUP.

1,393,304.

Specification of Letters Patent. Patented Oct. 11, 1921.

Application filed January 29, 1921. Serial No. 441,015.

To all whom it may concern:

Be it known that I, JACOB H. MILLER, a citizen of the United States, residing at Cresson, in the county of Cambria and State 5 of Pennsylvania, have invented certain new and useful Improvements in Grease-Cups, of which the following is a specification, reference being had to the accompanying drawings.

10 This invention relates to certain improvements in grease cups, and it has for an object to provide a device of this general character having novel and improved means whereby the lid is effectively maintained against 15 separation from the cup proper and wherein the lid is constructed in a manner to facilitate the desired application of the grease or kindred lubricant within the cup.

The invention consists in the details of 20 construction and in the combination and arrangement of the several parts of my improved grease cup whereby certain important advantages are attained and the device rendered simpler, less expensive and 25 otherwise more convenient and advantageous for use, as will be hereinafter more fully set forth.

The novel features of my invention will 30 hereinafter be definitely claimed.

35 In order that my invention may be the better understood, I will now proceed to describe the same with reference to the accompanying drawings, wherein:

Figure 1 is a vertical sectional view taken 35 through a grease cup constructed in accordance with an embodiment of my invention.

Fig. 2 is also a vertical sectional view taken 40 through my improved grease cup, the line of section being at substantially right angles to the line of section in Fig. 1.

Fig. 3 is a view in top plan of the device as disclosed in Figs. 1 and 2.

Fig. 4 is a horizontal sectional view taken 45 through the central portion of my improved device, and

Fig. 5 is a fragmentary view in top plan of the retaining ring as herein embodied.

As disclosed in the accompanying drawings, C denotes a grease cup having its inner wall threaded, as at 1, from end to end. The cup C is preferably of a type particularly adapted for use in connection with the side rods of a locomotive to lubricate a crank pin 50 coating therewith, although I do not wish

to be understood as limiting myself to this particular use.

L denotes the lid in its entirety for the cup C and said lid comprises an elongated tubular body 2 adapted to extend within 60 the cup C. The inserted end of the body 1 is open while the opposite or outer end is closed by the integral head 3. The marginal portion of the head 3 is defined by an outstanding flange 4 which coacts with the adjacent end of the cup C to limit the extent of movement of the lid L, or more particularly the body 2, inwardly of the cup C. The head 3 is also provided with an outstanding lug 5 angular in plan to provide 65 means whereby a wrench or other tool may be effectively engaged with the lid to properly and conveniently manipulate the lid.

The inserted end portion of the body 2 is provided with an outstanding continuous 70 flange 6, the periphery of which is relatively broad and has threaded engagement with the internal threaded wall 1 of the cup C so that upon requisite rotation of the lid L, the body 2 may be moved inwardly or outwardly 75 of the cup as desired.

After the inserted end portion of the lid L has been applied within the cup C, a retaining ring 7 is welded or otherwise securely affixed to the outer end or edge of the 80 wall of the cup C and said ring, when applied, has its inner marginal portion partially overlying the outer end of the cup C to provide a flange or stop 8 with which the flange 6 engages to limit the outward movement 85 of the lid. The ring 7 preferably comprises a plurality of sections so that the same may be properly arranged in applied or working position.

The wall of the body 2 is provided with a 90 longitudinally extending and relatively wide slot 9 extending from the flange 6 to a point immediately adjacent the head 3.

When the lid L is extended with respect 95 to the cup C, the hard grease or kindred lubricant may be readily placed within the body 2 thereof, to extend within the cup C. By 100 this arrangement, the grease or lubricant can be put in without the necessity of entirely removing the lid L and this is of particular importance as it avoids the damaging 105 of the threads 1 which often occurs in con- 110

nection with lids which are entirely separable from the cup. Furthermore, my improved type of grease cup prevents loss of the lids as so often occurs with the types of 5 grease cups now generally in use.

From the foregoing description it is thought to be obvious that a grease cup constructed in accordance with my invention is particularly well adapted for use by reason 10 of the convenience and facility with which it may be assembled and operated, and it will also be obvious that my invention is susceptible of some change and modification without departing from the principles and 15 spirit thereof and for this reason I do not wish to be understood as limiting myself to the precise arrangement and formation of the several parts herein shown in carrying out my invention in practice except as here- 20 inafter claimed.

I claim:

In combination with a grease cup having its inner wall threaded and provided at its outer end with an inwardly directed stop shoulder, a lid for said cup including a tubular body extending within the cup, the inserted end of the body having an outstanding flange in threaded engagement with the internal threads of the cup, the inserted end of the tubular body being open, and a wall of said body being provided with a slot extending longitudinally thereof, the outer end portion of the lid being provided with a permanent flange coacting with the cup to limit the movement of the lid inwardly of 30 the cup.

In testimony whereof I hereunto affix my signature.

JACOB H. MILLER.
